UNITED STATES PATENT OFFICE.

CHARLES W. DAKE, OF GRAND RAPIDS, MICHIGAN, ASSIGNOR TO THE GRAND RAPIDS CYCLE COMPANY, OF SAME PLACE.

DESIGN FOR A CRANK-BEARING BRACKET.

SPECIFICATION forming part of Design No. 27,576, dated August 24, 1897.

Application filed June 17, 1897. Serial No. 641,206. Term of patent 7 years.

To all whom it may concern.

Be it known that I, CHARLES W. DAKE, a citizen of the United States, residing at Grand Rapids, in the county of Kent, State of Michigan, have invented and produced a new and original Design for Crank-Bearing Brackets for Bicycle-Frames, of which the following is a specification, reference being had to the accompanying drawings, and to the letters of reference marked thereon, which form a part of this specification.

This invention relates to a design for crank-bearing brackets for bicycle-frames, and has for its object the production of a new and original design for crank-bearing brackets, as illustrated in the accompanying drawings, in which—

Figure 1 is a perspective view of my design. Fig. 2 is a plan view of same. Fig. 3 is a transverse section on line 3 3 of Fig. 2.

This bracket consists of a cylindrical shell A, having the short members B and C projecting at an angle from the periphery thereof and having the rearwardly-extending neck 25 or shank D, provided at its rear end with the

curved branches E. This neck D, connecting the curved branches E with the shell A, is elliptical in form, as clearly shown in Figs. 1 and 3, its major axis extending transversely thereof and in the direction of the longitude 30 of said shell, while the minor axis of said neck is through its vertical diameter.

The essential feature of my design consists in the cylindrical shell A and the curved branches E, united to said shell by the neck 35 D, which in cross-section is oblong to the extent that its major axis extends transversely thereof.

Having thus fully set forth my invention, what I claim as new, and desire to secure by 40 Letters Patent, is—

The design for a crank-bearing bracket for bicycles, substantially as herein shown and described.

In testimony whereof I affix my signature 45 in presence of two witnesses.

CHARLES W. DAKE.
